UNITED STATES PATENT OFFICE.

MORRIS KOSOFSKY, OF NEW YORK, N. Y., ASSIGNOR TO KENILWORTH MFG. CO., INC.,
OF NEW YORK, N. Y., A CORPORATION OF NEW YORK.

FASTENING MEANS.

Application filed December 14, 1922, Serial No. 606,782. Renewed June 23, 1926.

My invention relates to fastening means and more particularly to means whereby encircling bands of fabric or other material, such as the cuffs of knickerbockers, 5 waist-bands, garters, belts and the like are detachably fixed in their encircling position and has for its object to provide a novel and simple arrangement whereby the band will not only be efficiently secured in 10 place but in addition, will be automatically adjusted to properly fit the part of the anatomy which it encircles. Other more specific objects of the invention will appear from the description hereinafter and the 15 features of novelty will be pointed out in the appended claims.

In the accompanying drawings, which show an example of the invention without defining its limits, Fig. 1 is a perspective 20 view of a band of material in the form of a knickerbocker cuff with the invention applied thereto; Fig. 2 is an outer face view showing said band flattened out; Fig. 3 is an inner face view thereof with parts broken 25 away and Fig. 4 is a view similar to Fig. 3 showing the finished band.

For the purpose of illustrating and describing the invention I have shown the same in combination with a knickerbocker cuff to 30 which, by reason of its construction and operation, it is particularly adapted, although it will be obvious that the means is capable of being efficiently utilized in combination with any encircling band of material where an automatic adjustment as to 35 fit is desirable, such as waistbands, garters, belts and the like. It will accordingly be understood that the illustrated knickerbocker cuff is intended to be representative 40 of all such encircling bands. As shown the cuff comprises the customary band of fabric 10 cut in the desired shape and provided at one end with a fastening device of predetermined characteristics and illustrated in 45 the form of a button hole 11. Near its other end and on a line with the fastening device or button hole 11 the band is provided with a slit 12 having closed ends and extending lengthwise of the band, said slit being located 50 entirely between the ends of the band as shown in Fig. 2. A fastening member of a type adapted for detachable connection with the fastening device 11 and in the il-

lustrated example, comprising a button 13 is located upon the outer surface of the 55 band 10 in registry with the slit 12; the fastening member or button 13 is connected with a cord or other flexible loop 14 which extends inwardly through said slit 12 and in turn is attached to one end of an elastic 60 tape 15. The latter is located contiguous to the inner face of the band 10 and has its other end secured thereto in any conventional manner as by sewing 16.

With this arrangement the fastening 65 member or button 13 is located upon the outer surface of the band and is adjustably connected therewith by means of the elastic tape 15 which is located upon the inside of said band and the loop 14 which extends 70 through the slit 12. The button 13 or its equivalent thus has a range of movement upon the outer face of the band and entirely within the confines thereof in the direction of its length while the elastic tape 15 which 75 provides for the adjustability of the button 13 is entirely hidden from view; the loop 14, which is of relatively thin material such as cord, moves lengthwise of the slit and because of its physical characteristics does 80 not spread the same in a transverse direction to any appreciable extent.

In practice the end of the band 10 at which the button hole 11 or its equivalent is located is lapped over the other end thereof and the fastening member or specifically the button 13 is connected with the button hole 11. The elastic tension exerted by the tape 15 upon the connected button and button hole or their equivalents automatically 90 draws the band 10 about the part which it encircles, that is in the illustrated example draws the cuff 10 snugly about the leg to properly fit the same regardless of its dimensions. At the same time the tension exerted 95 by the tape 15 places the band or cuff 10 under a tension which is sufficient to prevent the slit 12 from spreading or gaping so that the loop 14 and also the tape 15 remain invisible from the front of the band regardless of the location and adjustment of the button 13 with respect to said slit 12.

In some cases it may be desirable to provide a covering 17 of suitable material upon the inside of the band 10 in registry with the slit 12 and preferably sewed in place as 100 105

indicated at 18; the covering 17 may be extended to completely cover the tape 15 although it is sufficient in most instances to simply locate said covering in registry with the slit 12. The covering 17 not only provides an attractive finish upon the inside of the band 10 but also, by providing a backing as it were for the slit 12, reduces the possibility of the button 13 unintentionally passing backward through said slit.

The invention provides a fastening means of extreme simplicity and efficiency and whereby the band of whatever nature it may be, is automatically adjusted to fit the part which it encircles; this result is accomplished automatically by the simple expedient of connecting the co-operating fastening devices and members with each other and requires no setting or adjusting of any of the elements of the combination. The invention is particularly adapted for use in connection with knickerbocker cuffs and provides the desirable trimness and permits the use of buttons and button holes which characterize high class garments of the knickerbocker type and are much desired. At the same time the invention may be used to advantage in connection with garters, waistbands, belts and the like, it being understood that the fastening device and fastening member, as exemplified by the button hole 11 and button 13, are always of a type predetermined by the character of the band 10 and the use to which it is to be put. In addition the arrangement is such that no part of the fastening means of the invention contacts with the person of the wearer, which is a desirable feature particularly in the case of garters.

Various changes in the specific form shown and described may be made within the scope of the claims without departing from the spirit of the invention.

I claim:

1. The combination of an encircling band of material provided with a fastening device, a cooperating fastening member movable lengthwise of the outer surface of said band and arranged for detachable connection with said fastening device to fix said band in its encircling position, said member having a range of movement entirely between the opposite ends of said band and which at no time extends beyond either end thereof, and elastic means on the inside of said band located entirely between said ends of the band and connected with said fastening member whereby the latter is placed under a tension to automatically fit said band in its encircling position.

2. The combination of a band of encircling material having a slit extending lengthwise thereof and located between the end confines of said band, the latter being provided with a fastening device, a cooperating fast-

ening member movable entirely within the end confines of the band lengthwise of said slit upon the outer surface of said band and adapted for detachable connection with said device to fix said band in its encircling position, an elastic tape located entirely within the end confines of the band upon the inside thereof and having its one end secured to said band, and a connection extending through said slit from the other end of said tape to said member whereby the latter is placed under a tension to automatically fit said band in its encircling position.

3. The combination of a band of encircling material having a slit extending lengthwise thereof and located between the end confines of said band, the latter being provided with a fastening device, a cooperating fastening member movable between the end confines of said band lengthwise of said slit upon the outer surface of said band and adapted for detachable connection with said device to fix said band in its encircling position, an elastic tape located entirely within the end confines of the band upon the inside thereof and having its one end secured to said band, a connection extending through said slit from said tape to said member whereby the latter is adjustably connected with said band to automatically fit the same in said encircling position, and a covering of material on the inside of said band in registry with said slit.

4. A leg cuff for knickerbockers comprising a band of material adapted to encircle the leg and provided with a slit extending lengthwise of and located between the end confines of said band, the latter being provided with a button-hole, a button adapted for connection with said button-hole and movable between the end confines of said band lengthwise of said slit upon the outer surface of said band, an elastic member located entirely within the end confines of the band upon the inside thereof and having its one end secured to said band, and a connection from the other end of said tape to said button whereby the latter is adjustably connected with said band to automatically fit the same about the leg under a tension whereby the slit is prevented from spreading to expose the tape and connection to view.

5. A leg cuff for knickerbockers comprising a band of material adapted to encircle the leg and provided with a slit extending lengthwise of and located between the end confines of said band, the latter being provided with a button-hole, a button adapted for connection with said button-hole and movable between the end confines of the band lengthwise of said slit upon the outer surface of said band, an elastic member located entirely within the end confines of the band upon the inside thereof and having its

- one end secured to said band, a connection from the other end of said tape to said button whereby the latter is adjustably connected with said band to automatically fit the same about the leg under tension whereby the slit is prevented from spreading to expose the tape and connection to view, and a covering of material located upon the inside of said band in registry with said slit whereby the button is prevented from unintentionally passing therethrough.
- 5
- In testimony whereof I have hereunto set my hand.

MORRIS KOSOFSKY.
